UNITED STATES PATENT OFFICE

RUDOLPH J. SAILER, OF TOWNLEY, NEW JERSEY, ASSIGNOR TO THE SINGER MANUFACTURING COMPANY, OF ELIZABETH, NEW JERSEY, A CORPORATION OF NEW JERSEY

SEWING MACHINE ATTACHMENT

Application filed February 20, 1932. Serial No. 594,255.

This invention relates to sewing machine parts and attachments which are shiftable from one to another position on the sewing machine. More particularly, the invention relates to sewing machine work-guiding attachments which are shiftable from a normal operative position to an out-of-the-way or inoperative position.

The invention has for an object to provide a sewing machine part or attachment with a simple and effective throw-in and throw-out mechanism which may be readily and quickly operated at the will of the operator and which will properly retain the part or attachment in either of its two positions without further attention of the operator and without the necessity of loosening and tightening fastening screws or of manipulating special locks, catches, or the like.

A further object of the invention is to provide for the ready adjustment of the attachment in its operative position without interfering with the functions or effectiveness of the throw-in and throw-out mechanism.

With the above and other objects in view, as will hereinafter appear, the invention comprises the devices, combinations, and arrangements of parts hereinafter set forth and illustrated in the accompanying drawings of two specific embodiments of the invention, from which the several features of the invention and the advantages attained thereby will be readily understood by those skilled in the art.

Fig. 1 is a front elevation of a work-guiding attachment or edge-guide embodying the invention and applied to the needle-bar-supporting head of a sewing machine. Fig. 2 is a side elevation of the device from the left of Fig. 1. Fig. 3 is a top plan view of the device shown in Figs. 1 and 2. Fig. 4 is a disassembled perspective view of certain of the parts of Figs. 1, 2 and 3. Fig. 5 is a front elevation of a work-guiding attachment or strip-folding guide embodying the invention in a modified form and arranged on the needle-bar-supporting head for movement of the attachment in an up-and-down direction

as distinguished from a lateral movement, such as indicated in Fig. 1. Fig. 6 is a view of the parts shown in dotted lines in Fig. 5. Fig. 7 is a perspective view of the supporting bracket member of the device and Fig. 8 is a top plan view of the device shown in Fig. 5.

Referring to Figs. 1, 2, 3 and 4, 1 is the usual head at the end of the sewing machine bracket-arm. Secured to the head 1 by screws 2 is the foot-plate 3 of a bracket 4 having an ear 5 bent at right angles to the plane of the body-portion 4 of the bracket. The screws 2 pass through vertical slots 6 in the foot-plate 3 to provide for vertical adjustment of the bracket 4 and the parts carried thereby.

Threaded into the bracket 4 is a shouldered pivot-screw 7 which supports a carrier-plate 8 flat against the body-portion of the bracket 4. The screw 7 also pivotally supports the carrier-lever 9 for the edge-guide 10. The carrier-plate 8 has an ear 11 bent at right-angles to it, so as to lie parallel to and spaced from the ear 5 of the bracket 4. There is threaded into the ear 11 the stem 12' of an adjusting screw 12, the grooved shank 13 of which passes through the vertical slot 14 in the ear 5 of the bracket 4. By means of the screw 12 a limited adjustment of the carrier-plate 8 may be made relative to the bracket 4; there being sufficient play between the side walls of the groove 13 and the faces of the ear 5 to permit of a limited tilting of the screw 12 from a right-angle position relative to the ear 5 as such screw moves circularly about the pivot-screw 7 as a center.

Pivotedly mounted at 15 on the carrier-plate 8 is an operating lever 16 which is connected by the link 17 to the edge-guide carrier-lever 9. The head of the lever 16 is formed with two angularly related straight edges 18 and 19 with an intermediate cam-nose 20. When the edge-guide 10 is in its operative or full-line position, Fig. 1, the straight edge 19 of the head of the operating lever 16 is in engagement with the edge-guide carrier-lever 9, which latter is in engagement with a stop-shoulder 11' constituted by one side of the ear 11 of the carrier-plate 8. The link 17 is also in or near alinement with the pivot-screw 15 so that the lever 16 and link 100

17 constitute a toggle-device which locks the edge-guide carrier-lever 9 against accidental displacement from its full line or operative position.

5 There is a further locking effect of the lever 16 upon the lever 9, independent of the locking effect of the toggle-device, due to the relation of the pivot-screw 15 to the straight edge 19 which latter constitutes a locking shoulder. This relation is such that a line *a*—*a* through the center of the pivot-screw 15 and the cam-nose 20 adjacent the end of the locking shoulder 19 is substantially normal to the locking shoulder, so that any force 10 tending to displace the edge-guide to the right, Fig. 1, is positively resisted or blocked by the portion of the head of the lever 16 directly between the lever 9 and the pivot 15.

By merely swinging the lever 16 upwardly 20 the operator may quickly and easily swing the edge-guide 10 to its out-of-the-way or inoperative position, shown in dotted lines in Fig. 1. There is a distinct binding or cramping action of the cam-nose 20 upon the lever 9 as the parts approach their dotted line 25 positions. This binding action of the cam-nose 20 upon the lever 9 at or near its out-of-the-way position is due to the shaping of the cam-nose 20 which is such that as the parts 30 are approaching their dotted line positions, the movement of the cam-nose 20 toward the right is somewhat slower than the movement of the lever 9 caused by the link 17. The binding or cramping action of the cam-nose 35 upon the lever 9 at the dotted line position of the parts, Fig. 1, prevents accidental displacement of the guide 10 from its out-of-the-way position.

The edge-guide, as shown in Figs. 1, 2, 3 40 and 4, is used to guide the edge of the crown-member 21 of a cap relative to the sewing machine needle *n* in the sewing thereto of a vizor 22 and sweat-band 23. The edge of the vizor 22 is positioned by the edge-guide 24 45 and the sweat-band 23 is positioned by the strip-guide 25. The vizor edge-guide 24 is secured by screws 26 to the cylinder-bed 27 of the sewing machine and is adjustable toward and from the needle *n* by virtue of the provision of slots 26' in the shank 24' of the edge-guide 24. The strip-guide 25 is provided with a block 28 adjustable within and widthwise of its passageway to accommodate sweat-bands of different widths. The strip-guide 25 is adjustably secured to the cylinder-bed 27 by the usual screw-and-slot expedient 50 55 29.

Referring now to Figs. 5, 6, 7 and 8, 30 represents the bracket-arm head of a sewing machine having two needles 31, a presser-foot 32 and a bed 33. Screwed to the head 30 is a bracket 34 on which a carrier-lever 35 is mounted by a pivot-screw 36. The pivot-screw 36 also passes through the underlying 60 65 carrier-plate 37 which is adjustably anchored

by the screw-and-slot expedient 38 to the bracket 34.

Fulcrumed on the carrier-plate 37 by means of the screw 39 is the throw-out lever 40 which is connected by the link 41 to the carrier-arm 35. The carrier-arm 35 is shown as carrying a strip-folding guide 42 such as is commonly used for shirt front centering operations.

The lever 40 has a straight edge or locking shoulder 43 which clamps the carrier-arm 35 against the stop-shoulder 43' of the carrier-plate 37 with the folding guide 42 in its operative or full-line position, in which position the link 41 is in or near alinement with the pivot-screw 39 and acts as a locking toggle-device. The lever 40 is also formed with a cam-nose 44 shaped to bind upon or cramp the lever 40 as the latter approaches its out-of-the-way position, Fig. 6, (also shown in dotted lines in Fig. 5), to prevent accidental displacement of the guide 42 from such position. This binding action is not so severe that it cannot be overcome by a purposeful downward movement of the lever 40 by the operator. It will be observed that the line *b*—*b*, Fig. 5, through the pivot-screw 39 and the end of the locking shoulder 43 adjacent the cam-nose 44 is substantially normal to the locking shoulder 43 in the full line position of the parts. Spring washers 7', 15', 36' and 39' are preferably provided on the respective pivot-screws 7, 15, 36 and 39 to facilitate manufacture by compensating for slight variations in stock thicknesses and screw length dimensions.

Having thus set forth the nature of the invention, what I claim herein is:—

1. In a sewing machine attachment, supporting means, an arm pivotally carried by said means for movement from operative position to an out-of-the-way position, a work-engaging device operatively connected to said arm, a manually operated lever fulcrumed on said supporting means, a link-connection between said lever and arm, and a cam-nose on said lever constructed and arranged to wedge against said arm at or near the out-of-the-way position of the latter.

2. In a sewing machine attachment, supporting means, an arm pivotally carried by said supporting means for movement from an operative position to an out-of-the-way position, a work-engaging device operatively connected to said arm, a stop, a manually operated lever having a locking shoulder for clamping said arm in operative position against said stop, and a link-connection between said lever and arm for retracting the latter to its out-of-the-way position, said lever having a cam-nose adapted to wedge against said arm as the latter approaches its out-of-the-way position.

3. In a sewing machine attachment, sup-

- porting means, an arm pivotally carried by said supporting means for movement from an operative position to an out-of-the-way position, a work-engaging element carried by 5 said arm, a manually operated lever fulcrumed on said supporting means, a link-connection between said lever and arm, said link-connection and the fulcrum of said lever being in or near alinement in the operative 10 position of the parts, and a cam-nose on said lever constructed and arranged to wedge against said arm at or near the out-of-the-way position of the latter.
4. In a sewing machine attachment, a bracket, a carrier-plate, a carrier-arm, a common fulcrum screw for said plate and arm, a work-engaging element on said carrier-arm, a manually operated lever mounted on said carrier-plate and connected to said carrier- 15 arm to rapidly shift the latter from an operative position to an out-of-the-way position, and means permitting said carrier-plate to be adjusted about said fulcrum screw for adjustment of said work-engaging element 20 in operative position.
5. In a sewing machine attachment, a support, an arm fulcrumed on said support, a work-engaging element operatively connected to said arm, a stop-shoulder for said arm 25 on said support, a manually operated lever fulcrumed on said support, means on said lever for locking said arm against said stop-shoulder, and a link-connection between said lever and arm for retracting the latter from 30 operative position.
6. In a sewing machine attachment, a pivotally mounted arm, a work-engaging device operatively connected thereto, a pivotally mounted operating lever, a link-connection 35 between said arm and lever, said lever having a cam-nose and a straight locking shoulder in engagement with said arm and substantially normal to a line through the fulcrum of said lever and said cam-nose when said arm is 40 in its normal operative position, said lever being movable to swing said arm out of operative position.
7. In a sewing machine attachment, a support, an arm fulcrumed on said support, a work-engaging element operatively connected to said arm, a stop-shoulder for said arm 45 on said support, a manually operated lever fulcrumed on said support, and a link-connection between said lever and arm for retracting the latter from operative position, said link being in or near alinement with the fulcrum of said manually operated lever when said arm is in engagement with said stop-shoulder.
8. In a sewing machine attachment, a support, an arm fulcrumed on said support, a work-engaging element operatively connected to said arm, a manually operated lever fulcrumed on said support and having a shoulder in engagement with said arm when said 50
- arm is in normal operative position, and a link connection between said lever and arm for retracting the latter, said link connection being in or near alinement with the fulcrum of said lever in the normal operative position 70 of the parts so as to act as a locking toggle device.
- In testimony whereof I have signed my name to this specification.
